Primary Examiner — S. Bryan Reinholdt, Jr.*Assistant Examiner* — James T Tyree(74) *Attorney, Agent, or Firm* — Daryl R. Wright; Greg Carr(57) **CLAIM**

The ornamental design for a model vehicle body assembly as shown and described.

DESCRIPTION

FIG. 1 is an upper, left, front perspective view of a model vehicle body assembly showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is an upper plan view thereof;

FIG. 7 is a lower plan view thereof;

FIG. 8 is an upper, right, rear perspective view thereof; and, FIG. 9 is a lower, right, rear perspective view of the model vehicle body assembly.

In the drawings, the broken lines illustrate portions of the model vehicle body assembly that form no part of the claimed design.
